BLADE SUPPORTING MEANS

Georges Monnet, New York, N. Y., assignor to
 Guardian Merchandising Corporation, Mont-
 real, Quebec, Canada, a corporation of Quebec,
 Canada

Application September 4, 1936, Serial No. 99,382

5 Claims. (Cl. 206—16)

This invention relates to blade supporting means and refers more particularly to supports carrying safety razor blades.

This patent application is a continuation in part of my co-pending patent application filed April 1, 1936, Serial No. 72,068.

Safety razor blades are usually packed individually in oiled paper and are enclosed in a paper envelope. Five, ten or a larger number of such envelopes are packed together in packages made of heavier paper or cardboard.

Past experience has shown that this method of wrapping razor blades does not prevent the sharp edges thereof from rubbing against the paper 15 wrapping so that often the ends become dull before the user removes the razor blade from its wrapping for the first time.

The user must first open the paper envelope to produce the razor blade wrapped in oiled paper, 20 then take off the oiled paper and finally place the razor blade upon the safety razor. All these manipulations must be done by hand and the razor blade must be held by the user before it is deposited upon the safety razor.

25 Everyday experience shows that the fingers or the hands of the user are frequently cut by the sharp edges of the safety razor blade while the blade is unwrapped and placed upon the safety razor.

30 During the unwrapping the sharp edges of the blade frequently come in contact with the wrapping and may be dulled by this contact. The form of the blade prevents the user from holding it securely with the result that the blade is often dropped and damaged; furthermore it is 35 extremely inconvenient and dangerous to pick up a dropped blade when it lies upon its flat surface.

An object of the present invention is the provision of blade supporting means of such form 40 that any contact between the fingers or the hand of the user and the razor blade is avoided while the blade is being unwrapped and placed upon the safety razor, thereby eliminating the danger of injury to the user.

45 Another object is the provision of blade supporting means which will effectively protect the sharp edges of the blades while the latter are not in use.

The above and other objects of the present invention may be realized through the provision of 50 a blade which consists of two parts, namely, the blade proper and a support for the blade which preferably is made of a sheet of resilient flexible material such as metal and which is provided with 55 means holding the blade in position and prevent-

ing its sharp edges from being dulled by contact with any part of the wrapping.

The sheet of flexible material constituting the blade support is wider than the blade and is of such form that it may be held by the user while 5 he is placing the blade upon the safety razor. Thus any contact between the fingers of the user and the razor blade proper is avoided and the danger of injury is substantially eliminated.

The invention will appear more clearly from 10 the following detailed description when taken in connection with the accompanying drawing showing by way of example preferred embodiments of the inventive idea.

In the drawing:

Figure 1 is a perspective view of a support carrying a blade.

Figure 2 is a section along the line 2—2 of Figure 1.

Figure 3 shows a razor blade support of a some- 20 what different type.

Figure 4 is a section along the line 4—4 of Figure 3.

Figures 5 and 6 show different forms of razor 25 blade supports.

Figure 7 is a section through a package containing a plurality of razor blades.

While the safety razor blade 10 (Fig. 3) may be of any standard make it is preferred to use razor blades having two sharp cutting edges and two 30 tongue ends 11 of a width less than the total width of the blade so that shoulders 12 are formed on opposite sides of each tongue end of the blade.

The blade support 30 shown in Figures 1 and 2 of the drawing may be made of cardboard, metal 35 or any other suitable firm but flexible or resilient material, the surfaces of which are preferably waterproofed by waxing or by any other appropriate means. Preferably the support 30 is wider than the blade 10 so that when the support is 40 picked up by the fingers of the user there is no danger that the user will be cut by the sharp edges of the razor blade 10.

The blade support 30 is provided with flaps or 45 bent over portions 31 and 32 which have cut out portions 33 and 34, respectively. The tongue ends 11 of the blade 10 pass through the openings 33 and 34 respectively, and fit snugly into these openings so that any shifting of the blade 10 upon the support 30 is prevented.

The middle portion of the support 30 is preferably provided with two parallel ridges 37 and 38 (Fig. 2) so that the blade 10 rests upon these ridges and not upon the flat surface of the support. The flap 31 is provided with similar parallel 55

ridges 39 and 40 while the flap 32 is provided with parallel ridges 41 and 42. By this arrangement the blade 10 is conveniently supported without contacting the entire surfaces of the support.

- 5 In order to place the blade upon a safety razor the user must keep one flap, for instance, the flap 32 closed, and open the flap 31 thereby freeing one end of the razor blade. This freed end of the razor blade is first placed upon the safety 10 razor and then the support 30 is removed, leaving the blade in its proper position upon the safety razor. The support 30 will prevent injury to the fingers of the user, since at no time does the user hold the blade between his fingers while 15 moving it from its envelope and placing it upon the safety razor.

The support 13 shown in Figures 3 and 4 of the drawing is preferably made of metal which has a different resiliency than the blade 10. The 20 support 13 is wider and longer than the blade 10 and is provided with upturned flanges 14, 15, 16 and 17. Due to this arrangement the support 13 has the form of a shallow container, the side walls of which prevent contact with the sharp 25 edges of the blade. The form of the support 13 is such that it will successfully withstand any type of pressure exerted upon it.

The blade is firmly held upon the flat surface of the support 13 by means of four lugs 18 which 30 extend adjacent the shoulders 12 of the blade and are in contact with the side edges of the tongue ends 11. Due to this arrangement the blade 10 is firmly held upon the support 13.

The support 13 is provided with a central opening 19 which is preferably longer than the usual 35 central opening 20 of the razor blade 10 and of the same width and design. Then the projecting portions of a safety razor may extend through the openings 19 and 20 while the blade is placed 40 in proper position upon the safety razor and the support 13 is bent to release the blade.

As shown in Figure 3 the support 13 is provided with several notches or cut out portions 21, the purpose of which is to increase the resiliency of the support.

When the user removes the support 13 from the envelope his fingers do not come in contact with the blade 10 due to the provision of the upturned flanges 14 and 16 so that the user can 50 hold the support conveniently between his fingers. In order to be able to place the blade 10 upon a safety razor, the user must hold the support 13 between the fingers of one hand and gently move the edge 17 of the support toward 55 the edge 15 thereby bending the support in the middle. Then the lugs 18 will slide off the shoulders 12 of the blade, and the blade may be placed or dropped in proper position upon the safety razor. Due to the provision of the notches 60 21, the support 13 may be readily bent to a somewhat greater extent than the blade 10 thereby facilitating the withdrawal of the lugs 18 from the shoulders 12.

The razor blade support 22 shown in Figure 5 65 consists of a substantially flat piece of metal having no upturned edges and is provided with lugs 23 which hold the blade in position. The support 22 has a central opening 24 and a number of perforations 25, the purpose of which is 70 to increase the resiliency of the support.

The blade support 26 shown in Figure 6 of the drawing is provided with lugs 27 for holding the blade and has two parallel upturned flanges 28 and 29. The other two sides of the support are 75 flat.

The support 26 comprises a central opening 45 and two smaller openings 46 situated on both sides of the central opening 45. Slits 47 lead from the openings 46 to the edges of the upturned flanges 28 and 29 respectively. Due to this arrangement the resiliency of the support 26 is increased so that the support can be easily bent and the blade 10 can be conveniently freed and placed upon a safety razor.

Razor blades and other supports may be sold 10 to the customer in packages of any convenient form. One of such packages is shown in section in Figure 7 of the drawing. The packages comprise five razor blades 10 each of which is carried by a separate support 13 and is placed one 15 on top of the other. Each blade and its support may be enclosed in an individual envelope or wrapper 48 consisting of wax paper or any other suitable material. All the blades and their supports are enclosed in a cardboard container 49. 20

The present invention is not intended to be restricted to any particular construction or arrangement of parts or manner of use or to any various details herein shown and described, as the same may be modified in various particulars or 25 be applied in many varied relations without departing from the spirit and scope of the claimed invention, the practical embodiments herein illustrated and described merely showing some 30 of the various features of the invention.

What is claimed is:

1. Blade supporting means, comprising a single support for a single razor blade, said support being in the form of a shallow tray of firm but bendable material, the edges of the tray extending 35 at sufficient distance beyond the confines of the corresponding edges of the blade to be supported to permit grasping and bending of the tray without contacting the blade, and readily releasable means carried by said tray to detachably secure 40 said blade upon the tray, said means being located in spaced relation with respect to the apex of bend of the tray, so that upon bending of the tray the blade will be released.

2. Blade supporting means, comprising a single 45 support for a single razor blade, said support comprising a sheet of firm but bendable material, said sheet having outer edges constituting the outlines of the support and at least two opposed inner edges, at least some of said outer edges extending at sufficient distance beyond the confines 50 of the corresponding edges of the blade to be supported to permit grasping and bending of the support without contacting the blade, the apex of bend of the support extending between said opposed inner edges, and readily releasable means carried by said support to detachably secure said blade upon the support, said means being located in spaced relation with respect to the apex of 55 bend of the support, so that upon bending of the support the blade will be released.

3. Blade supporting means, comprising a single support for a single razor blade, said support comprising a sheet of firm but bendable material, said sheet having a central opening formed there- 65 in and at least one other opening situated between said central opening and an edge of the support, at least two opposite edges of the support extending at sufficient distance beyond the confines of the corresponding edges of the blade to 70 be supported to permit grasping and bending of the support without contacting the blade, the apex of bend of the support extending through said other opening, and readily releasable means carried by said support to detachably secure said 75

blade upon the support, said means being located in spaced relation with respect to the apex of bend of the support, so that upon bending of the support the blade will be released.

- 5 4. Blade supporting means, comprising a single support for a single razor blade, said support comprising a sheet of firm but bendable material, said support having at least one notch formed therein, at least two opposite edges of the support 10 extending at sufficient distance beyond the confines of the corresponding edges of the blade to be supported to permit grasping and bending of the support without contacting the blade, the apex of bend of the support extending through said 15 notch, and readily releasable means carried by said support to detachably secure said blade upon the support, said means being located in spaced relation with respect to the apex of bend of the

support, so that upon bending of the support the blade will be released.

- 5 5. Blade supporting means, comprising a single support for a single razor blade, said support being in the form of a shallow tray of firm but bendable material, the edges of the tray extending at sufficient distance beyond the confines of the corresponding edges of the blade to be supported to permit grasping and bending of the tray without contacting the blade, said tray having a 10 plurality of notches formed therein, the apex of bend of the support extending through one of said notches, and lugs carried by said tray to detachably secure said blade upon the tray, said lugs being located in spaced relation with respect to the 15 apex of bend of the tray, so that upon bending of the tray the blade will be released.
